CLAIM

The ornamental design for a light string, as shown and described.

DESCRIPTION

FIG. 1 is a first perspective view of a light string showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion in FIG. 1;

FIG. 10 is an enlarged view of the selected portion in FIG. 7; and,

FIG. 11 is an enlarged view of the selected portion in FIG. 8.

The broken lines shown in the drawings depict portions of the light string in which the design is embodied that form no part of the claimed design. The dash-dot-dash lines shown in FIGS. 1, 7-8 and 9-11 surrounding the detail views are for annotating the enlargements and form no part thereof. The light string is shown with symbolic breaks in its length. The break lines and the appearance of any portion of the light string between the break lines forms no part of the claimed design.
